UNITED STATES PATENT OFFICE.

DAVID RENSHAW, OF SYRACUSE, NEW YORK.

IMPROVEMENT IN SECTIONAL STEAM-BOILERS.

Specification forming part of Letters Patent No. 123,793, dated February 20, 1872.

Specification of certain Improvements in Steam-Generators, invented by DAVID RENSHAW, of Syracuse, in the county of Onondaga and State of New York.

Nature and Object of the Invention.

This invention relates to the construction of steam-generators made in sections, in which portions of the parts which generate steam are inclosed in a reverberatory furnace. The said invention consists, in part, in constructing the arch or crown of the furnace in cast-metal sections in the manner hereinafter described; and also, in part, in the combination of other parts hereinafter described.

Description of the Accompanying Drawing.

Figure 1 is a front elevation of a generator constructed according to my invention, one-half of the front or outside shield being removed and the sides of the crown being represented in section to give a clear view of the internal parts. Fig. 2 is a side view of the internal parts and base and a section of the top and sides of the crown.

General Description.

A A are the sides, and B B the ends of the upper portion of a furnace which forms a part of my invention, the said sides and ends forming parts of a reverberatory furnace, being, also, thus made capable of generating steam; these sides and ends being cast in whole sections, secured by stay-bolts a a cast with and forming a part of the same casting as the section to which they belong. The sizes of these sections may be varied according to circumstances so as to make them easily made and adapted to the convenience of the user, and of sufficient strength to bear safely the strain to which they are to be subjected. The ends B B may be cast in two sections each, joined at the center, as shown in the drawing; or may be divided in smaller sections, according to convenience or preference; but I prefer to make the sides A in sections of about eighteen inches in width, extending from the top down to the large horizontal pipes C. These sections A and B should all be bolted firmly together where they join each other, and should all connect with each other, particularly at the top, so that the steam generated in all of them can pass to the pipe D, and through it into the steam-drum E; or separate pipes may be carried up from each section to the drum E. For the purpose of bolt-

ing these sections together they should be cast with flanges, as shown at b b; and these flanges should be very exactly fitted and put together with rust or cemented joints on the outside and plain surface-joints on the inside. C C are large horizontal pipes, cast in a single piece each, and laid across from side to side of the furnace, as shown, and having heads c at their ends bolted upon them and fitted with plain surface-joints, said heads c being outside of the furnace, so that they can be readily removed for the purpose of cleaning the pipes C. These pipes C are also connected together by the side sections d d, cast in the same piece with them and secured by bolts and suitable plain surface-joints. The said pipes C also have sections or parts f f cast upon them, as shown, to receive the central vertical pipe F and the curved pipes G G, all of which may be of cast-iron. The pipes F may be cast in one piece with steam-drum E, if preferred; but I prefer to make them with sections cast with the said steam-drum, extending down just inside of the crown of the furnace, and the portions below, cast separate and secured to them by surface-joints and bolts, so that the main portions of these pipes F may be removed and replaced, if desired, without disturbing the crown of the furnace. The curved pipes G G are also attached, by surface-joints and bolts, to the sections f, as shown, and also to the sections g cast upon and forming parts of the pipes F in the same manner. The steam-drum E is provided with gauge-cocks h to determine the height of the water. H is the base or lower part of the furnace, which may be made up of cast-metal sections, forming water-legs, which first receive the water pumped in by the supply-pump through the feed-pipes I, or any one or more of them, and from the base H connections may be made with the pipes C, or one or more of them, to supply them and the pipes connected with them with water by means of pipes J, K, and L, as shown in the drawing. L is a blow-off pipe attached to the lower part of the base H, and connected also with the pipes C, or one or more of them, by means of the pipe K. The sections which make up the base H are so constructed as to form a flaring top to the furnace, as shown at i, giving an inclined surface, on which the ashes will readily descend so as to fall upon the grate M. It will be desirable to have return-flues in the generator so as to more effectually utilize the

heat from the fire; and these flues may be returned through the upper portion of the water-space, forming the reverberatory arch of the furnace in the position shown by the cap *j* in Fig. 1; or through the base *H* in the position shown by the cap *k* in Fig. 2; or any other position may be given to the flues that may be desirable. *l* is a feed-opening between the sections of the base *H*, and *m* is a hand-hole for cleaning the base *H*. In the drawing the corners where the front and sides of the upper portion of the furnace are united are represented as being angular; but I prefer to make these corners rounded or curved so as to avoid angles in the castings; and I prefer to do this with relation to any other parts of the furnace where curves can be adopted instead of angles. *N* is the fire-door, and *n* is the ash-pit of the furnace. I recommend the use of a water-pan in the ash-pit to clean the grate and for other purposes. It will be observed that the upper part of the furnace is made in the form of a reverberatory furnace, and it will, therefore, to a certain extent, operate in that capacity, while, it being made hollow and supplied with water, it will also serve to generate steam. Of course, as a portion of the heat is absorbed by it in the generation of steam, that portion of the heat will not be reverberated by it, and it will not be so entirely reverberatory as a furnace of the same form made of non-conducting material. It may be a question on which good engineers might differ, whether or not for stationary boilers it is desirable to construct a furnace in the manner above described and shown in the drawing, or to construct it of brick; but in locomotive-engines, where brick is not admissible, this construction which I have described is of very great advantage, and aids to economize the heat and to make a complete and perfect locomotive steam-generator, which may be entirely of cast-iron (except the necessary bolts) and brought into a very compact form. The furnace portions of the generator, being properly stay-bolted in the manner above described, are very strong, and sufficient strength can thus be secured at moderate cost to safely allow a much higher working pressure than boilers, as generally constructed, whether of cast or wrought iron, can safely carry. It will be observed that, as the stay-bolts are cast with and form a part of the single casting of which each section is made, their number can be cheaply increased, and they are cast in with a very little additional labor.

The combination of the cross-pipes *C*, the central vertical pipes *F*, the curved pipes *G*, and the steam-drum *E* inclosed in a proper furnace, and especially in one having reverberatory power, results in many important advantages, among which may be mentioned that it secures the most satisfactory and stable bearing of the evaporating parts on the supports in a locomotive-engine of any boiler which has yet been produced. It furnishes a more compact boiler in proportion to its working capac-

ity than is produced by the ordinary constructions. It secures an excellent circulation of the water—an extraordinary economy in evaporation—while, at the same time, a steam-generator constructed in this way is very safe, and can be constructed at moderate cost.

The combination, with the horizontal pipes *C* extending across over the fire, of the central vertical pipe *F*, connecting directly with the cross-pipes *C* and the covered pipes *G*, also connecting at intervals directly with the said cross-pipes *C* and with the vertical pipes *F*, is of very important advantage, and produces a circulation of the water which would not be realized by an indirect connection of the curved pipes *G* with the ends of the horizontal or cross pipes *C*.

The combination of the heads *e* or their equivalent with the cross-pipes *C*, the vertical pipes *F*, and the curved pipes *G* is very important, as the construction of the pipes *F* and *G* and their combination with the pipes *C* is such that the sediment formed in said pipes *F* and *G* is discharged into the pipes *C*; and, by combining therewith the removable heads *e*, this sediment, which is formed in all parts of this internal boiler, can be readily removed and the boiler kept in good working condition.

Claims.

I claim as my invention—

1. A fire-chamber or reverberatory furnace made up in sections, such sections or any number of them being cast in a single piece of each and stay-bolted, substantially as hereinbefore set forth.

2. The combination of a fire-chamber or furnace made up of sections, such sections or any number of them being cast in a single piece each and stay-bolted, with steam-generating apparatus contained within said furnace, substantially as hereinbefore set forth.

3. The combination of the horizontal cross-pipes *C*, the vertical pipes *F*, connecting directly with the pipes *C*, and the pipes *G*, also connecting directly with the pipes *C* at their lower ends, and with the pipes *F* at their upper ends, substantially as hereinbefore set forth.

4. The combination of the horizontal cross-pipes *C*, the vertical pipes *F*, connecting directly with the cross-pipes *C*, the pipes *G* also connecting directly at intervals with the cross-pipes *C* and the steam-drum *E*, substantially as hereinbefore set forth.

5. The combination of the horizontal cross-pipes *C*, the vertical pipes *F* connecting directly with the said pipes *C*, the pipes *G* also connecting directly with the said pipes *C* at their lower ends and with the pipes *F* at their upper ends, and the removable heads attached to the ends of the horizontal pipes *C*, substantially as hereinbefore set forth.

DAVID RENSHAW.
